UNITED STATES PATENT OFFICE.

HARRY E. LEWIS, OF HARLAN, IOWA.

FOLDABLE SLIP-TRAY FOR COMPUTING-MACHINE STANDS.

1,166,062.

Specification of Letters Patent. Patented Dec. 28, 1915.

Application filed May 22, 1915. Serial No. 29,898.

To all whom it may concern:

Be it known that I, HARRY E. LEWIS, a citizen of the United States, residing at Harlan, in the county of Shelby and State of Iowa, have invented certain new and useful Improvements in Foldable Slip-Trays for Computing-Machine Stands, of which the following is a specification.

My invention relates to the general class of office furniture, and particularly to hinged, swinging or foldable shelf and drawer attachments for stands, desks, or the like.

It is the object of my invention to provide a device particularly adapted for use with stands for accounting and computing machines, providing conveniently located trays for holding loose papers such as checks, deposit-slips and the like within easy reach of the machine operator, and so that piles of the slips or loose sheets will not be disarranged by jars or vibration such as result from the operation of machines of the class mentioned.

A further object of my invention is to provide trays or holders, as above described, which may be adjusted to various angular positions with respect to the stand on which the device is mounted, which may be folded to provide a flat-topped table or leaf such as is commonly used on such stands, and which may be moved, after folding, to a position enabling the table or leaf to be turned down from a horizontal to a vertical position.

Further and more specific objects of my invention will appear hereinafter.

In the accompanying drawings, Figure 1 is a perspective view of a device embodying my invention, the same being in open position ready for use, Fig. 2 is an end view of the same in folded and lowered position, Fig. 3 is a view of the inner side when in folded and lowered position, Fig. 4 is a longitudinal vertical section of the device in open position, Fig. 5 is an end view of the device in use as a plain shelf, Fig. 6 is a bottom view illustrating the angular adjustments, Fig. 7 is a detail longitudinal section of the angle-adjusting latch and slide-bar, and Fig. 8 is a detail transverse section on the plane of the line $x-x$ of Fig. 7.

In the drawings I have illustrated portions of a common and extensively-used stand for computing machines, with which my invention is particularly adapted for

use, the stand comprising a frame formed principally of tubular metal members, and being adapted to support the computing machine at a suitable height. The parts of the stand indicated, in Figs. 1, 2, 3 and 5, are the upper portions of two of the legs 1, an end cross-rod 2 connecting the legs, front and rear cross-bars 3 and 4, and front and rear shelf-standards 5 and 6. The usual position of the computing machine, relative to the parts mentioned, is indicated by dotted lines A in Fig. 1.

In the ordinary construction of the stand, a simple swinging shelf or leaf is hinged to the upper ends of the standards 5 and 6, being swingable from a vertical lowered position to a horizontal raised position at which it forms a support for books, papers or the like, to which the operator of the computing machine may desire to refer.

In the construction illustrated herein, my improved device is substituted for the ordinary shelf or hinged leaf, and there is provided a shelf or leaf having a main body portion 7 with longitudinal side-pieces 8 which extend forward from the portion 7 and of which the inner edges are shouldered or rabbeted. To the front edge of the body portion 7 a leaf-portion 9 is connected therewith by means of hinges 10, the longitudinal edges of said leaf-portion being shouldered or rabbeted so as to fit between the forwardly-extending parts of the side-pieces 8, as shown in Figs. 2 and 5. From the closed or extended position shown in said figures the leaf 9 is swingable about its hinge-axis to an open or inverted position as shown in Figs. 1 and 4. In the lower side of the shelf, near the front edge of the portion 7, a metal cross-bar 11 is laid in a transverse groove therein, the ends of said bar extending out beneath the side-pieces 8 and being secured thereto so as to securely hold said pieces against spreading apart. On the lower sides of the side-pieces 8, adjoining the inner edges thereof, guide-strips 12 are secured thereto, said strips extending back to a cross-piece 13 which extends transversely across the rear end of the leaf on the lower side thereof, being secured to the portion 7 and to the rear ends of the side-pieces 8.

For connecting the shelf with the standards 5 and 6, a metal hinge-bar 14 is provided, having laterally-turned end-portions which fit against the heads of the standards

and are pivotally connected therewith by screws 15. The end of the hinge-bar near the front standard 5 is pivotally connected with one of the guide-strips 12 at a point 5 slightly in front of the center of said strip, the connection being formed by a screw 16. At the other end of the hinge-bar a slide bar 17 is pivotally connected therewith by means of a pin or rivet 18. On the adjacent end 10 of the cross-piece 13 a channel-plate 19 is pivotally connected with said cross-piece by means of a screw 20, as shown in Fig. 7, and the flanges of said channel-plate fit slidably around the edges of the bar 17. On the up- 15 per or back side of the channel-plate one end of a flat spring 21 is secured thereto, and the opposite end of said spring carries a latch-pin 22 which projects into one of a series of holes in the bar 17 to retain the 20 channel-plate in adjusted relations to said bar. On the end of the spring adjacent to the latch-pin 22 there is secured a thumb-piece 23 which projects out rearwardly so that it may be grasped to raise the spring 25 and disengage the latch-pin from the bar 17, as shown by dotted lines in Fig. 7, there being a suitable notch or recess in the lower side of the cross-piece 13, to permit the lifting of the spring. The end of the channel- 30 plate opposite the pivot-screw 20 is held slidably in proximity to the cross-piece 13 by means of an angle-plate 24 of which a vertical portion is secured to the cross-piece and a horizontal portion extends beneath 35 the channel-plate, as shown in Figs. 4 and 7.

To the end of the cross-bar 11 opposite the hinge-bar 14 there is pivotally connected the upper end of a brace-rod 25, of which the lower end is reduced to form a pin 26 40 adapted to enter a hole in the cross-rod 2 of the stand, as shown in Fig. 5. Said brace-rod serves to support the shelf in the horizontal or raised position shown, and, when disengaged from the cross-rod 2, permits the 45 shelf to drop down to the lowered position thereof shown in Figs. 2 and 3. The hole in the rod 2 for the pin 26 is arranged so as to be in vertical alinement with the pivot-screw 16 when the shelf is in the horizontal raised 50 position.

Normally, or when the shelf is in the lowered position, the hinge-bar 14 extends parallel with the adjacent side-piece 8 of the shelf, and the latch-pin 22 is engaged with 55 the slide-bar 17 so that said bar and the channel-plate 19 extend parallel with the end of the shelf adjoining the cross-piece 13. After the shelf is raised to the horizontal 60 position, however, the latch-spring 21 may be raised as described, and the rearward end of the shelf swung outwardly to an angular position with respect to the hinge-bar and the stand, the outward swinging movement being made about a vertical axis extending 65 through the pivot-screw 16 and the pin 26

at the lower end of the brace-rod 25. By engaging the latch-pin 22 with a suitable one of the holes in the slide-bar 17, the shelf is retained in any desired angular relation to the stand, characteristic angular positions 70 thereof being shown in Fig. 1 and by dotted lines in Fig. 6. In moving to the angular positions the slide-bar 17 swings about the axis of the pin 18, and the channel-plate 19 swings about the axis of the screw 20, as 75 will be apparent from Fig. 6.

The inner sides of the guide-strips 12 have channels or grooves 27 therein, and fitting slidably in said grooves are tongues 28 which extend out from the upper edges of a sliding 80 tray formed by side-pieces 29, an end-piece 30 and bottom 31. On the side-pieces 29 are secured stop-plates 32 which are adapted to engage similar stop-plates 33 secured on the guide-strips, to limit forward sliding movement of the tray. Rearward sliding movement of the tray is limited by engagement of the rear end thereof with the cross-piece 13.

Inside the guide-strips 12, above the 90 grooves 27 therein, are disposed a second or upper set of guide-strips, of which the rearward portions 34 are secured to the shelf-portion 7, while the forward portions 35 are secured to the hinged leaf 9. When the leaf 9 is in extended position, between the side-pieces 8 of the shelf as shown in Fig. 5, the grooves in the inner sides of the guide-strips 34 and 35 are alined to form continuous ways or guides for laterally-projecting tongues 100 on the sides of an upper tray which is formed by a transverse piece 36, inner and outer side-pieces 37 and 38, and an end-piece 39. The upper tray is slightly narrower than the lower, so that the side-pieces 37 and 38 105 may fit within the side-pieces 29 of the lower tray, while the end-piece 39 fits into the open end of the lower tray. On the end-piece 39 is pivoted a hook 40 which may be engaged with a pin 41 on the front end of the bottom-piece 31 of the lower tray to hold the two trays together in the folded position 110 thereof assumed when the leaf 9 is extended, as in Fig. 5. The upper tray has a longitudinally-extending partition 42 secured there- 115 in, and the lower tray has a transversely-extending partition 43. The ends of the partition 43 are cut away, and the central part thereof is notched or recessed, as shown, to provide longitudinal spaces for receiving 120 the side-pieces and the partition 42 of the upper tray, when in folded position.

When the leaf-portion 9 is extended and the guide-strips 34 and 35 are thus alined longitudinally with each other, both the upper and lower trays may slide longitudinally in their respective guides, the two trays forming in effect a single box or drawer of which the two parts are secured to each other by the hook 40 and by another con- 130

necting device described hereinafter. When the trays are pushed back into engagement with the cross-piece 18, and the hinged shelf is swung down to the lowered position thereof, the trays pass into the space between the standards 5 and 6, as shown in Figs. 2 and 3. After the shelf is raised to the horizontal position, and either before or after the same is swung out to the angular position thereof, the trays may be pulled forwardly until the stops 32 and 33 are in contact, and at this position the front end of the lower tray is flush with the front ends of the guide-strips 12, while the upper tray is supported entirely by the guide-strips 35 on the hinged leaf 9, the rear end of the upper tray being slightly in front of the joint between the leaf 9 and the shelf-portion 7. For convenience in pulling the trays forwardly, a hook-plate 44 is secured on the bottom of the lower tray, as shown. After the trays are in the forward position, and the hook 40 being disengaged from the pin 41, the leaf 9 may be raised and swung back upon its hinges until it lies in an inverted position on top of the shelf-portion 7, and during such movement it carries with it the upper tray, so that at the conclusion of the movement the parts are in the positions shown in Figs. 1 and 4.

After the swinging back of the leaf 9 has been commenced, both the upper and lower trays are prevented from moving longitudinally of their respective guides, by means of a special connecting device, of which the construction and operation may be understood by reference to Figs. 1 and 4. On the front side of the end-piece 30 of the lower tray a metal plate 45 is secured, and at the upper end of said plate are forwardly-extending lugs between which a small roller 46 is revolvably mounted. On the adjacent end of the piece 36 of the upper tray a resilient tongue 47 is pivotally connected therewith, and said tongue extends down between the roller 46 and the plate 45, so as to be vertically slidable with respect thereto. The resilient hinged tongue 47 forms a variable or yieldable and sliding connection between the adjacent ends of the upper and lower trays, permitting the upper tray to be swung back to open position, and preventing any considerable movement of either tray longitudinally of its guides, except when the trays are in folded position and both are moved simultaneously. At an intermediate position during the opening or unfolding movement, the tongue 47 is bent as indicated by the dotted lines in Fig. 4.

When the trays are folded, but in the forward position thereof at which the upper tray is carried upon the lower side of the leaf 9, raising of the leaf may be prevented by the engagement of the hook 40 with the pin 41, and the parts 7, 8 and 9 then form

a plain flat-topped table or shelf which may be used to support books or the like, the same as the ordinary shelf or table hereinbefore referred to, but having the advantage of being swingable to various angular positions by releasing the latch-pin 22 and swinging the rear end of the shelf outward, as before described. When the sliding trays are pushed back from the forward position thereof, so that the tongues of the upper tray are engaged with both the front and rear guide-strips 35 and 34, said tongues prevent the leaf from swinging upwardly if the shelf is in horizontal position, or, if the shelf is in the lowered or vertical position thereof, the leaf is prevented from swinging outwardly, since the trays when pushed back to their extreme rearward position still overlap the joint between the guide-strips 34 and 35.

When the trays are in the open position shown in Figs. 1 and 4 they form suitable receptacles for holding loose papers such as checks, vouchers, drafts, deposit-slips, and the like, in convenient and accessible position for the operator of the computing machine A. Piles of the slips are supported and held in the various compartments of the trays, so that they cannot be blown away and cannot be disarranged by jars or vibration resulting from the operations of the machine, such as the rapid return of the carriage. By the outward swinging of the shelf to the angular positions shown and described, the trays are so disposed that the operator of the machine may look directly into the same, and so that the slips may be easily reached and transferred from one compartment to another as they are successively referred to. By the arrangement of one tray above as well as behind the other, the contents of both are at substantially equal distance from the eye of the operator, and both may be observed with equal facility. The stepped arrangement of the trays may be considered as substantially the same as the arrangement of the banks of keys on the keyboard of the computing machine. The inner side-piece 37 of the upper tray is made lower than the outer side, thereby not tending to obstruct the view of the operator; while the high outer side 38 forms an abutment against which the slips may be thrown when transferring them rapidly from the inner to the outer compartment of the tray. Obviously, in the use of the device it will usually be most convenient for the operator to first place the piles of slips to be referred to in the inner compartment of the upper tray, or in the front compartment of the lower tray, and to transfer the slips to the outer and rear compartments of the respective trays as the items on the successive slips are entered or posted by the use of the machine.

- When the machine is not in use the tray mechanism may be quickly folded and returned to the lowered position thereof, the operations required being merely the turning 5 of the leaf 9 forward, engaging the hook 40 with the pin 41, pushing the trays to the rearward position, releasing the latch-pin 22 and swinging the rear end of the shelf inwardly, then slightly lifting the shelf to 10 disengage the brace-rod 25 from the rod 2, and finally lowering the shelf to the vertical position; while a reversal of these operations will place the trays in open or unfolded position ready for use.
- 15 Now, having described my invention, what I claim and desire to secure by Letters Patent is:
1. In a device of the class described, the combination with a support, of a hinge-member pivoted thereon and swingable on a horizontal axis, a shelf pivotally connected with said hinge-member, a slide-bar pivoted on said hinge-member, means for connecting the slide-bar and shelf in varying relations, 20 and a brace-bar pivotally connected with the shelf at a point remote from the hinge-member and adapted to engage the support at a point vertically aligned with the pivotal connection between the shelf and hinge-member to sustain the shelf in horizontal 25 position and enable the swinging thereof about a vertical axis while in said horizontal position.
  2. In a device of the class described, a shelf having a hinged leaf-portion, a lower tray supported on a relatively fixed portion of the shelf, an upper tray adapted to fit in an inverted position within the lower tray, and means for connecting the upper tray 30 with the hinged leaf-portion whereby said tray may be turned over with said leaf-portion to a position displaced both vertically and horizontally from the lower tray.
  3. In a device of the class described, a shelf having a hinged leaf-portion, guides carried upon a relatively fixed body-portion of the shelf, a lower tray slidable longitudinally along said guides, an upper tray adapted to fit within the lower tray, guides 35 for said upper tray having parts carried by the hinged leaf and other parts carried by the body-portion of the shelf, and means connecting the trays to cause substantially coincident longitudinal movement thereof 40 along their respective guides, the upper tray being invertible by movement of the hinged leaf when said tray is supported by the parts of the guides on said leaf.
  4. In a device of the class described, the combination with a swinging shelf and spaced supporting-standards with which the shelf is pivotally connected so as to be movable from a lower vertical position to a raised horizontal position, of trays carried by the 45 shelf and slidable thereon parallel with the

pivotal axis of the shelf about the standards, said shelf having at one end an invertible portion, and means thereon for engaging one of the sliding trays, the trays being movable longitudinally to a position 70 beneath the invertible portion from a position adjoining the space between the standards, and being swingable from the latter position into said space between the standards when the shelf is moved from horizontal to vertical position.

5. In a device of the class described, a shelf having at one end a hinged portion swingable to inverted position upon the main body of the shelf, longitudinal guides 80 secured on the main body of the shelf, a lower tray slidable in said guides, other guides having portions secured on the main body and portions secured on the hinged invertible portion, an upper tray slidable in 85 the latter guides and adapted to fit within the lower tray, a resilient tongue pivotally connected with one end of the upper tray, and a part secured on an adjacent portion of the lower tray and connecting slidably 90 with said resilient tongue.

6. In a device of the class described, a shelf having a hinged invertible leaf-portion, a lower tray, means for connecting the same with the shelf, an upper tray adapted 95 to fit within the lower tray, means for connecting the upper tray with the invertible leaf-portion, a support for the shelf, means pivotally connecting the shelf and support whereby the shelf may be moved about a 100 vertical axis, and means for retaining the shelf in various angular relations to the support.

7. In a device of the class described, a support, a hinge-member pivoted thereon 105 and swingable on a horizontal axis, a shelf pivoted on said hinge-member, means for supporting said shelf in a horizontal plane, means for retaining the shelf while in the horizontal plane in various angular relations to the hinge-member, the shelf having a hinged invertible portion, a tray connected 110 with the shelf, and a second tray adapted to be moved with the hinged invertible portion from a position within the first tray to a 115 position at which it is displaced both vertically and longitudinally therefrom.

8. In a device of the class described, a shelf having a main body and a portion hinged thereto, guide-strips having parts secured on the main body and other parts secured on said hinged portion, said parts of the strips being longitudinally aligned when the hinged portion is in one position, and a tray having tongues slidable along 120 said guide-strips, said tongues at one position of the tray engaging both parts of the guide-strips to retain the hinged portion in alignment with the main body, and at another position engaging only the hinged 125

portion, the tray at the latter position being swingable with the hinged portion.

9. In a device of the class described, a shelf having a main body and a portion hinged thereto, guide-strips having parts secured on the main body and other parts secured on said hinged portion, said parts of the strips being longitudinally alined when the hinged portion is in one position, a tray having tongues slidable along said guide-strips, said tongues at one position of

the tray engaging both parts of the strips to retain the hinged portion in alinement with the main body and at another position engaging only the hinged portion, the tray 15 at the latter position being swingable with the hinged portion, a second tray slidably connected with the main body only, and means connecting the trays to secure them against dis-simultaneous sliding movement. 20

HARRY E. LEWIS.
